CLAIM

The ornamental design for a lighting fixture, as shown and described.

DESCRIPTION

FIG. 1 is a bottom perspective view of a lighting fixture showing my new design;

FIG. 2 is right end elevational view thereof, the left end being a mirror image;

FIG. 3 is a bottom plan view thereof;

FIG. 4 is a front elevational view thereof;

FIG. 5 is a top plan view thereof; and

FIG. 6 is a rear elevational view thereof.

FIG. 7 is a bottom perspective view of a lighting fixture showing an alternative embodiment of my new design; and FIG. 8 is right end elevational view thereof, the left end being a mirror image, and the bottom plan, front elevational, top plan, and rear elevational views thereof being the same as FIGS. 3-6.

FIG. 9 is a bottom perspective view of a lighting fixture showing another alternative embodiment of my new design;

FIG. 10 is bottom plan view thereof, the right end elevational view thereof being the same as FIG. 2, and the left end being a mirror image;

FIG. 11 is a front elevational view thereof;

FIG. 12 is a top plan view thereof; and

FIG. 13 is a rear elevational view thereof.

FIG. 14 is a bottom perspective view of a lighting fixture showing a further alternative embodiment of my new design;

FIG. 15 is right end elevational view thereof, the left end being a mirror image;

FIG. 16 is a bottom plan view thereof;

FIG. 17 is a front elevational view thereof;

FIG. 18 is a top plan view thereof; and,

FIG. 19 is a rear elevational view thereof.

FIGS. 1, 3-7, 9-13, 14 and 16-19 are broken away to indicate indeterminate length. The broken lines in FIGS. 5-6, 12-13, and 18-19 represent the bounds of the claimed design; the region within these broken lines forms no part of our claimed design. The curved shield portion of the lighting fixture shown in FIGS. 9-13 is shaded for translucency. The broken line showing of folded over tabs in FIGS. 14-17 is for illustrative purposes only and forms no part of the claimed design embodiment shown in FIGS. 14-19.
